UNITED STATES PATENT OFFICE.

JAMES R. STEWART, OF CHICAGO, ILLINOIS.

DESIGN FOR A COMBINED PEG HEAD AND NECK FOR A STRINGED MUSICAL INSTRUMENT.

Application filed April 26, 1926. Serial No. 17,460. Term of patent 14 years.

To all whom it may concern:

Be it known that I, JAMES R. STEWART, a citizen of the United States, residing at Chicago, in the county of Cook and State of Illinois, have invented a new, original, and ornamental Design for a Combined Peg Head and Neck for Stringed Musical Instrument, of which the following is a specification, reference being had to the accompanying drawings, forming a part hereof.

In the drawings, Fig. 1 is a top plan view

of a peg head and neck for stringed musical instruments embodying my new design.

Fig. 2 is a fragmentary side elevation of Fig. 1.

Fig. 3 is an end elevation of the peg head.

I claim:

The ornamental design for a combined peg head and neck for a stringed musical instrument as shown.

JAMES R. STEWART.
